UNITED STATES PATENT OFFICE.

FRANK H. HOUGHILLAND, OF ST. LOUIS, MISSOURI.

BOX.

SPECIFICATION forming part of Letters Patent No. 681,322, dated August 27, 1901.

Application filed December 15, 1900. Serial No. 39,976. (No model.)

To all whom it may concern:

Be it known that I, FRANK H. HOUGHILLAND, a citizen of the United States, residing at St. Louis, in the State of Missouri, have invented 5 a certain new and useful Improvement in Boxes, (Case A,) of which the following is a specification, reference being had to the accompanying drawings.

This invention relates to paper boxes or 10 cartons of that class which are designed to fold flat for ease of shipment and which can be very easily formed into box shape when it is necessary to use them; and the object of 15 my present invention is to form a box of this character which can be made very inexpensively and which can be sealed so as to be "germ-proof" or can be folded into shape and "locked" into that shape without the necessity of sealing by gluing or otherwise.

20 With this object in view my invention consists in a box or carton of the peculiar construction and arrangement of parts herein-after described in detail and then set forth in the claims appended hereto.

25 In the drawings accompanying and forming part of this application, Figure 1 is a plan view of the blank out of which the body of the box is made. Fig. 2 is a perspective view of the body partly folded. Fig. 3 is a side 30 elevation showing the locking-sheet partly inserted, and Fig. 4 is a plan of the locking-sheet.

Referring now to the details of the drawings by numerals, 1 represents the blank, which is 35 made out of a simple rectangular sheet of paper, cardboard, or desired material, preferably without any cuts therein. This blank is creased or scored entirely across its top and bottom, as shown at 2 and 3, and at four 40 places at right angles thereto, as shown at 4, 5, 6, and 7, thus forming the sides of the box 8, 9, 10, and 11 and the pasting or gluing strip or flap 12. These creases also mark out the parts composing the top and bottom of 45 the box, which are marked 14, 15, 16, and 17 and 18, 19, 20, and 21. Before the blank is pasted the top and bottom parts 15 and 17 and 19 and 21 are further creased at 15^a, 17^a, 19^a, and 21^a. The blank is now pasted and 50 the part 12 secured to the inside of the part 8. The box as thus glued is all ready to be shipped, and unless it is desired to form a

germ-proof box or carton this one gluing is all that is necessary, as will hereinafter appear.

When it is desired to "set up" the box ready for use, it is opened into square form, as shown in Fig. 2, and the top and bottom folded as follows: The parts 19 and 21 are folded inwardly on their creases 19^a and 21^a, 55 a form or mandrel being first inserted in the box, if desired. One side of a locking-sheet 22 (see Fig. 4) is now inserted in the pocket formed between the part 18 and the folds of parts 19 and 21. The other end of the locking-sheet is then placed in the opposite pocket, when the parts are in a similar position to that shown in Fig. 2. The hand of the operator is now pressed on the locking-sheet and the parts 18 and 20 and all are pressed 60 into position. If it is desired to make this end of the box absolutely rigid or to make it germ-proof, either the locking-sheet or the insides of the pockets may be covered with any suitable adhesive material. If a form or 65 mandrel has been used, it is now withdrawn, the box filled, and the top closed in a manner similar to that just described.

If it is desired to ship food compounds or 70 similar articles, it is preferable to paste each locking-strip in place; but if such articles as lamp-chimneys are shipped the pasting may be dispensed with, in which case the box is 75 preferably made the proper length to contain the article, and the friction of the locking- sheet will keep the ends from being opened 80 by accident and the article in the box will prevent the ends from being accidentally pushed in.

85 From an inspection of the accompanying drawings it will be seen that I have invented an exceedingly simple and cheap box or carton, one which can be used without pasting the ends, if desired, and which by pasting becomes absolutely germ-proof. It will be observed 90 that by using a separate locking-sheet which is not formed in one piece with the body of the box the advantage is attained of making it possible to use a blank consisting of a simple rectangular sheet of paper or pasteboard without any cuts therein, and there is therefore no waste, inasmuch as nothing is cut away from the blank and thrown away. It will also 95 be noticed that the ends have several folds 100

- or thicknesses of material which act when not glued as a cushion to prevent breakage in shipping when a number of these boxes are packed end to end. The square locking-
5 pieces also protect the ends, making them rigid and strong and thoroughly bracing them. It will also be noticed that there is no place for the box to rip at the corners, as there is no starting place or corner to begin ripping.
- 10 I do not intend to limit my claims to a box in which the locking-sheet is pasted within the opposing pockets; as it will be seen by the mere act of crowding the two ends of the sheet into the box the box is closed.
- 15 What I claim as new is—
1. A blank box having at its ends foldable parts adapted to form opposing pockets, and a locking-sheet adapted to be inserted into said pockets by bending the same and fore-
20 ing said sheet down upon the box end and thereby closing the box, substantially as de-
scribed.

2. A blank box having at its ends foldable parts adapted to form opposing pockets, and a locking-sheet adapted to have its ends inserted in said pockets by bending the sheet, and by forcing said pockets and the inclosed locking-sheet down upon the box end and thereby closing the box, substantially as de-
25 scribed.

3. A blank box having at its ends foldable parts adapted to form opposing pockets, and a plain-faced locking-sheet adapted to be inserted in both of said pockets and to close the box by the mere act of such insertion, 35 substantially as described.

In testimony whereof I affix my signature, in the presence of two witnesses, this 5th day of December, 1900.

FRANK H. HOGHLAND.
